SCREEN-DOOR CHECK.

1,117,253.

Specification of Letters Patent.

Patented Nov. 17, 1914.

Application filed December 10, 1913. Serial No. 805,804.

To all whom it may concern:

Be it known that we, EDWARD R. SARGENT and EGBERT H. EGGLESTON, citizens of the United States, residing in the city and county of New Haven and State of Connecticut, have invented certain new and useful Improvements in Screen-Door Checks, of which the following is a full, clear, and exact description.

10 This invention relates to door checks, and more particularly to checks for screen doors and other light doors.

The primary object of the invention is to provide a simple, reliable and cheap door check of the pendant type wherein a suspended buffer on the door is thrown by centrifugal force, as the door closes, into contact with the jamb, after which, as the door rebounds, the buffer swings inward to clear 20 the door jamb, and permit the door to close with decreased force. More particularly, it is aimed to provide a door check having improved means for mounting, guiding and limiting movement of the buffer hanger, and 25 provided with an improved form of hanger and an improved form of buffer.

To these and other ends, the invention consists in the novel features and combinations of parts to be hereinafter described 30 and claimed.

In the accompanying drawing, Figure 1 is a fragmentary perspective view of a door equipped with a door check embodying our improvements; Fig. 2 is a side elevation of 35 door check; Fig. 3 is a rear view of the check, showing it detached from the door; Fig. 4 is a section on line 4-4 of Fig. 3; Fig. 5 is a detail of the buffer disk; and Fig. 6 is a detail of the fastening socket 40 for the hanger.

Referring to the drawing, the improved door check is shown as comprising a hanger 10, secured to the door 11, by means of a socket piece or cap 12, and screw 13, and carrying at its lower end a buffer disk 14. The hanger 10 preferably consists of a metal rod or heavy wire having an upper end portion 15, adapted to lie close to the face of the door, and a lower end portion 16, 45 offset from the end portion 15, so as to lie about parallel to the door, at some distance therefrom, the portions 15 and 16 being joined by an integral bent portion 17. The upper end portion 15 is provided with a hook or eye 18, through which passes the shank of the screw 13, for the purpose of se-

curing the hanger to the door. The eye 18 fits a seat 19 at the under surface of the fastening cap 12, whereby said eye 18 is covered, the eye being guided for oscillation between the seat 19 and the front surface of the door. The pivot for the eye is formed by a flange 30 extending inward around the opening 31 in the cap, through which the screw 13 is inserted. The fastening cap 12 is provided in its rim portion 12^a with a clearance opening 12^b, for the hanger shank, whereby the hanger is permitted to oscillate about the axis of the screw 13, but, at the same time, limited in its oscillatory movement. The hanger is normally suspended vertically, as shown in Fig. 3, and the clearance opening 12^b in the rim or flange of the fastening cap permits a slight swinging movement of the hanger on both 75 sides of a vertical plane passing through the point of suspension.

In order to securely fix against dislocation the fastening cap 12, which determines the extent of oscillation of the hanger, said cap is provided on the rim 12^a with a spur 12^c adapted to penetrate the door and to prevent angular movement of the cap about its axis.

The buffer 14 is in the form of a disk 85 which is made of rubber, or rubber compound, and is freely rotatable in a horizontal plane on the lower end portion 16 of the hanger. The disk 14 is held on the hanger by means of an upset head 20 on 90 the hanger shank, supporting a washer 21, which in turn supports the disk.

When the door is forcibly closed, the hanger and buffer will be swung outward by centrifugal force, so that the buffer will 95 strike the door jamb 22, as indicated by the dotted lines in Fig. 1. As the door rebounds and is slowed down, the hanger gradually moves back to its vertical position, wherein the buffer 14 clears the door 100 jamb and permits the door to close. The swing of the hanger is effectively limited by the slot in the rim of the fastener cap, and said cap suspends and guides the upper end 105 of the hanger for easy movement about the pivot.

The device may be very readily applied to the door, as the same screw which suspends the hanger secures to the door the cap which guides the hanger eye, and limits the 110 oscillatory movement of the device. As the buffer 14 is free to turn about the hanger

shank, wear on the buffer will not be localized, but will, on the other hand, be distributed quite uniformly over the peripheral surface of the disk, so that the latter will retain its shape indefinitely.

Without limiting ourselves to the construction shown, we claim:

1. A screen door check, comprising a buffer, a hanger therefor having an eye, a cap fitting over said eye, and means to secure the cap to the door, said cap having a clearance opening with a side edge to limit the swing of the hanger; substantially as described.

15 2. A screen door check, comprising a buffer hanger bent at one end to form an eye, a cap to fit over said eye, a side wall on the cap having a clearance opening for the buffer hanger, adapted to limit the 20 swinging movement of said hanger in both directions, and means for securing the cap and hanger eye to the door; substantially as described.

25 3. A screen door check, comprising a buffer hanger having an eye, and an inclosing cap for said eye adapted for attachment to the door, and having a pivot for said eye, forming a part of said cap; substantially as described.

30 4. A screen door check, comprising a buffer hanger having an eye, a cap having a flange on which said eye is rotatably supported, and means for securing said cap to the door; substantially as described.

35 5. A screen door check, comprising a buffer hanger having an eye, an inclosing cap for said eye having an opening, an inwardly projecting flange about said open-

ing adapted to extend into said eye, and a member adapted to extend through said opening, and to secure said cap to the door; substantially as described.

6. A screen door check, comprising a hanger rod having substantially parallel upper and lower end portions offset from each other, the upper end of said rod having an eye, a guiding member for said eye confining the latter between said member and the face of the door, and a buffer on the lower end of the rod; substantially as described.

7. The combination with a door, of a cap applied to the face of the door and having an opening at its lower part, and a buffer device having a shank extending upward into the cap through said opening and suspended from the door beneath the cap, said opening being formed and located to permit a swinging movement of the buffer device but to limit such swinging movement; substantially as described.

8. The combination with a door, of a cap applied to one face of the door, and a pendant buffer device having a hanger shank pivoted to the door beneath said cap and limited in its swinging movement by engagement with said cap; substantially as described.

In witness whereof, we have hereunto set our hands on the 8th day of December, 1913.

EDWARD R. SARGENT.
EGBERT H. EGGLESTON.
